(57) **CLAIM**

The ornamental design for a water heater [electric], as shown and described.

DESCRIPTION

1. Water heater [electric]

Electric water heater with a curved housing; a control panel with a round rotary knob is arranged in the middle of the upper third of the front.

FIG. 1.1 is a front view of water heater [electric];

FIG. 1.2 is a rear view thereof;

FIG. 1.3 is a top view thereof;

FIG. 1.4 is a bottom view thereof;

FIG. 1.5 is a right side view thereof;

FIG. 1.6 is a left side view thereof; and

FIG. 1.7 is a front perspective view thereof.
